UNITED STATES PATENT OFFICE.

ALPHONSE MASON, OF BOSTON, MASSACHUSETTS, ASSIGNOR TO COCHRANE MANUFACTURING COMPANY, OF EAST DEDHAM, MASSACHUSETTS, A CORPORATION OF MASSACHUSETTS.

DESIGN FOR CARPET.

SPECIFICATION forming part of Design No. 35,816, dated March 11, 1902.

Application filed February 17, 1902. Serial No. 94,566. Term of patent 3½ years.

To all whom it may concern:

Be it known that I, ALPHONSE MASON, of Boston, county of Suffolk, State of Massachusetts, have invented and produced a certain 5 new and original Design for a Carpet, fully described in the following specification and represented in the accompanying drawing, forming a part of the same.

The design is intended to be worked into or 10 upon carpets or similar fabrics in such colors as may be desired; and I do hereby declare that the drawing accompanying this specification conveys to one skilled in the art of carpet weaving and manufacture a clear understanding of the same and is sufficient to enable such person to use my invention.

The design is characterized by the prominent conventionalized flower-clusters A, the 15 fleur-de-lis B, overlaid thereupon, the over-

arching leaf-like scrolls C about the clusters, 20 and the arabesque figures D between the leaf-like scrolls, the clusters A being arranged in diagonal rows relatively to the length of the carpet and the leaf-like scrolls and their connecting arabesque figures being arranged 25 transversely of the carpet.

What I claim as new, and desire to secure by Letters Patent, is—

The design for a carpet, substantially as 30 herein shown and described.

In testimony whereof I have signed my name to this specification in the presence of two subscribing witnesses.

ALPHONSE MASON.

Witnesses:

GEO. W. GREGORY,
HERMAN J. SARTORIS.
